HYDRAULIC PUNCH AND STRIPPER

Otto Mueller, Dearborn, Mich.

Application January 18, 1947, Serial No. 722,935

27 Claims. (Cl. 164—95)

1

The present invention relates to hydraulic punching and stripping devices, and more particularly relates to a unit device for operating metal working tools and a pressure plate for holding and stripping the material from the tool, and generally constitutes an improvement over the structure disclosed in United States Letters Patent 2,353,488, issued July 11, 1944, for Hydraulic Punch and Stripper.

The primary object of the present invention is to provide a punch and stripper which may be of a unitary construction and adapted to be assembled alone or with the same or other units on a base or table or incorporated in a press or die unit for punching holes in sheets of metal.

Another object of the present invention is to provide a punch and stripper mechanism in which a piston, movable in a fixed cylinder, drives a tool supporting head carrying a punch and pressure plate, which plate is operable by an auxiliary piston in the tool supporting head to clamp a piece of work while the same is punched and the punch stripped therefrom.

Another object of the present invention consists in the provision of a punch and stripper including a compound cylinder movable on a fixed piston, having an auxiliary piston thereon movable with and independently of said compound cylinder, and carrying a punch and a pressure plate, which plate is operable by the auxiliary piston to clamp a piece of work while the punch is forced through and stripped from the work.

A further object of the present invention is to provide a punch and stripper unit of the type described which is carried on a resiliently restrained member actuated by a piston in the unit to bring a punch and pressure plate into operative engagement with a piece of work in cooperation with a second punch and pressure plate which is also actuated into operative engagement with the work by the piston.

The invention further contemplates apparatus of the type mentioned for punching holes in the opposed sides of channel members or other similarly shaped metal structures through use of opposed punching means.

Still further, the present invention contemplates apparatus of the type described for punching holes in opposed sides of channel members in which a single punch member is adapted to penetrate opposed sides or walls of a piece of work.

Other objects and features of novelty of this invention will be specifically pointed out or will become apparent when referring, for a better

2

understanding of the invention, to the following description taken in conjunction with the accompanying drawings, wherein:

5 Fig. 1 is a plan view of the punching device embodying the improvements of the present invention;

Fig. 2 is a sectional view of the structure illustrated in Fig. 1, taken on the line 2—2 thereof;

10 Fig. 3 is a view of structure, similar to that illustrated in Fig. 2, showing the punch in retracted position;

Fig. 4 is a sectional view through the ram structure, taken on the line 4—4 of Figure 2;

15 Fig. 5 is a sectional view of the structure illustrated in Fig. 2, taken on the line 5—5 thereof;

Fig. 6 is a broken sectional view of structure embodying a further improvement of the present invention;

20 Fig. 7 is a sectional view of the structure illustrated in Fig. 6, taken on the line 7—7 thereof;

Fig. 8 is a plan view of a further form of the present invention;

25 Fig. 9 is a sectional view of the structure illustrated in Fig. 8, taken on the line 9—9 thereof;

Fig. 10 is a broken sectional view of the structure illustrated in Fig. 9, taken on the line 10—10 thereof;

30 Fig. 11 is a sectional view of still another form of the present invention;

Fig. 12 is a sectional view of the structure shown in Fig. 11, taken on the line 12—12 thereof;

35 Fig. 13 is a sectional view of structure illustrating a further form of the invention;

Fig. 14 is a sectional view of the structure illustrated in Fig. 13, taken on the line 14—14 thereof;

40 Fig. 15 is a plan view, partly in section, of a further form of the invention, having the structure illustrated in Fig. 13 embodied therein;

Fig. 16 is a sectional view of the structure illustrated in Fig. 15, taken on the line 16—16 thereof;

45 Fig. 17 is a sectional view of the structure illustrated in Fig. 16, taken on the line 17—17 thereof;

Fig. 18 is a view of structure, similar to that illustrated in Fig. 15, showing a still further form 50 which the invention may assume, and

Fig. 19 is a sectional view of the structure illustrated in Fig. 18, taken on the line 19—19 thereof.

55 The apparatus of the present invention is intended for use with one or more punches and

may be assembled in gangs for punching holes in work of considerable length. For the purpose of simplification in the description, only one punch of the unit is described. However, it is not intended to limit the invention thereby.

Referring to Figs. 1 to 5, inclusive, one form of the present invention is illustrated. This embodies a metal punch and stripper having a base 10 of suitable proportions and strength to support the device when mounted on the shop floor or a table such as found in the ordinary shop or which may be a part of the base of a press or die unit. At longitudinally opposed ends of the base 10, upwardly directed brackets 12 and 14 are secured. On the inner, upright face of the bracket 14, which is at the right as viewed in Figs. 1 and 2, a member 16 is anchored, having an annular bore 18. A piston 20, which may be formed integral with a ram 22, is adapted to register within the opening 18 in the member 16, with the ram 22 extending outwardly thereof through a cap member 24, closing the end of the bore 18.

At the opposite end of the ram 22, that is to say, the left end as viewed in Figs. 1 and 2, a member 26 on a carriage 30 is secured by bolts 32. The carriage 30 is an L-shaped member mounted on the base 10 with the short leg thereof disposed perpendicular to the plane of the base and the long leg thereof mounted on machined ways 34 provided on the upper surface of the base. As may be clearly seen in Fig. 5, the long leg of the carriage 30 is mounted on the ways 34 of the base 10 between upwardly directed shoulders 36 formed on opposite sides of the base and retained therein by a pair of overlying keeper bars or gib members 38 bolted to the shoulders 36.

In the upwardly directed leg of the carriage 30, openings such as indicated at 42 in Fig. 2 are provided which are counterbored in the forward face of the upwardly directed leg to provide shoulders 44. In each of the openings 42, an annular cylinder 46 is press-fitted and a shoulder portion 48 on each cylinder is brought into abutting relationship with the shoulder 44. Each of the cylinders 46 is provided with an annular blocked opening 50 in which a piston 52 is positioned for movement in reciprocation. The forward ends of the openings 50 in the cylinders 46 are closed by a head 54 which is bolted to the face of the upwardly directed leg of the carriage 30. A plurality of punches 56 are retained by a punch holder 58 secured to the head 54.

A pressure plate 60 is mounted on the head 54 by spacers 62 through which bolts 64 extend and which are threaded into the cylinder head 54. The pressure plate 60 has counterbored openings 66 containing shoulders 68 which are in abutting relationship with shoulders 70 on the spacers 62 when the punches 56 are in a retracted position, as illustrated in Fig. 3. The inside diameter of the smaller portion of the counterbored openings 66 is slightly larger than the outside diameter of the spacers 62 to permit the shifting of the pressure plate 60 axially along the spacers as the punches 56 advance through openings 72 in the pressure plate. This permits the punching end of the punches 56 to enter into operative engagement with a piece of work 74, retained in punching position by the pressure plate.

A die block 78 is mounted on the bracket 12 in which a plurality of dies 80 are positioned having counterbored openings 82 disposed in alignment

with the punches 56 which are capable of passing thereto. Thus, when the punches 56 are brought into operative engagement with the work 74, each punch is forced through the workpiece 74 and the slug pressed therefrom is advanced into the enlarged portion of the opening 82 in each die and thence discharged by way of a mating opening 84 formed in the bracket 12 outwardly thereof.

The carriage 30 may be advanced to bring the pressure plate 60 and the punches 56 into engagement with the work 74 in any manner, so long as it provides for rigidly and positively holding the work 74 during the punching and stripping operations. For the purpose of illustration, the carriage 30 is shown as being actuated by the piston 20 which is hydraulically operated. Fluid under pressure is introduced into a port 88, a passageway 90 and the bore 18, causing the piston 20 and the carriage 30 to advance in the direction of the work 74.

A plunger 92 is positioned for slidable movement within a collar 94 secured in the blocked end of each of the cylinders 46 by nuts 95. A port 96 is provided in the collar 94 in axial alignment with the plunger 92 and connected by a flexible tubing or other suitable means 98 to a port 100 at the bottom of the member 26 in communication with the passageway 90. Thus, as fluid under pressure enters the bore 18 to move the piston 20 outwardly thereof, it simultaneously enters port 96 by the passageways just described, forcing the head end of the plunger 92 into contact with the adjacent face of the piston 52, causing the same to advance toward the head 54. Rods 104 extend between the opposite face of the pistons 52 and the pressure plate 60 through apertures in the head 54. As the carriage 30 moves toward the workpiece 74, the pressure plate 60 contacts one side of the work 74 and is forcibly held thereagainst, as illustrated in Fig. 2, by the rods 104 due to the action of the plunger 92 on the piston 52. The continued movement of the carriage 30 thereafter advances the punches 56 and the spacers 62 relative to the pressure plate 60 to perform the punching operation on the work 74. The forward movement of the carriage 30 is interrupted when the punch holders 58 engage the pressure plate 60. As the spacers 62 and punch 56 are moved forwardly relative to the pressure plate 60, the rods 104, the piston 52 and the plunger 92 are retracted in the cylinders 46. As the punch 56 passes completely through the work 74, the punched-out slug 108 is carried by the forward end of the punch into the enlarged portion of the opening 82 in the die 80 from which it will eventually drop as additional slugs collect and are advanced therein.

At the termination of the punching operation, the flow of pressurized fluid is reversed by a reversing valve (not shown) and the fluid is directed into port 110, thence through the passageways 112 and 114, and through the reduced passageway 116 into the bore 18 on the opposite side of the piston 20 to effect movement of the piston and the carriage 30 in a direction away from the work 74. A portion of the passageway 114 is formed in the movable ram 22 which opens into another passageway 118 and thence to a port 120. The port 120 is connected by a flexible tube to a port 124 communicating with the interior 50 of the cylinder 46. When pressure is applied to the rearward face of the piston 52, the piston is advanced toward the forward end of the cylinder

46, as the piston 20 is being retracted, maintaining the work 74 in clamped position.

The passageway 116 is smaller than the passageway 114 which provides a full flow of fluid and pressure upon the piston 52 before the piston 20 moves. As pressure builds up on the piston 20, the carriage 30 is moved away from the work 74, withdrawing the punch therefrom as the work is maintained in clamped position. The advancement of the piston 52 and the rod 10 104 as the piston 20 is retracted holds the pressure plate 60 against the work 74 throughout the retracting and stripping action, after which the passageway 114 is closed to fluid as the return of the carriage 30 is continued. As the punch 56 15 is being retracted, the continued movement of the carriage 30 away from the work 74 causes the spacers 62 to slide in the opening 66 in the pressure plate 60. After the stripping operation, the shoulder 70 engages the shoulder 68 formed in opening 66 and the pressure plate 60 is carried away from the work 74 with the punch and carriage until the piston 20 reaches retracted position. It is to be understood, of course, that when pressurized fluid is admitted to one or the other of the ports 88 or 110, the fluid in the unpressurized portion of the system is returned to tank (not illustrated).

In the form of the invention illustrated in Figures 6 and 7, there is shown a punch and stripping unit which is movable on a fixedly mounted ram. A ram member 130 is provided, which may be the ram of a press or die unit, fixed to a machine or other element to rigidly support the movable mechanism. A piston 132 on the ram 130 is positioned within a bore 134 of an inner hydraulic cylinder 136 which forms a portion of the movable part of the unit. An outer housing 138 of the unit also serves as a hydraulic cylinder and is provided with an annular opening 140 in which a floating piston 142 is positioned to move slidably on the inner wall of the opening 140 and the outer wall of the inner cylinder 136. The annular opening 140 of the housing 138 and the open end of the bore 134 in the cylinder 136 are closed by a cylinder head 144 having an opening through which the ram 130 extends. The opposite end of the opening 140 in the housing 138 is closed by a cylinder head 146 which abuts the closed end of the cylinder 136 and is secured in position by a plurality of bolts 148.

The housing 138 is mounted upon ways 150 formed on a base 152 which may be part of a base of the supporting element or of a die unit. On opposed sides of the base 152, shoulders 154 are provided between which the housing 138 may be retained by overlying keeper bars or gibs 156 bolted to the shoulders 154.

To provide for mounting a punch 160, a punch holder 162 is secured to the forward face of the cylinder head 146. A pressure plate 164 is mounted on the housing 138 by means of a plurality of bolts 165 and annular elongated nuts 166. The nuts 166 are slidably positioned in counter-bored openings 168 in the cylinder head 146. When the punch 160 is in fully retracted position, a shoulder 170, formed in the opening 168, is in engagement with a shoulder 172 formed on each of the nuts 166.

A die 174 is positioned in line with the punch 160, having a central annular opening 176, the diameter of which is just slightly greater than the diameter of the reduced end portion of the punch. The die 174 is retained in a holder 178 75 146 and thereby holds the pressure plate 164

which, in turn, is anchored to a supporting member 180 which may be formed integral with the base 152. Thus, after positioning a piece of work 182 with one face thereof against the die 174 and the die holder 178, it is possible to punch an opening in such work when the punch 160 is forced therethrough due to the action of the unit.

To effect movement of the unit on the ram 130, fluid under pressure may be introduced by way of a passageway 184 into the bore 134 of cylinder 136. With the ram 130 fixedly mounted, the cylinder 136 is thereby caused to move toward the left, as viewed in Figure 6, moving the housing 138 and the punch 160 toward the work 182. Simultaneously, fluid on the opposite side of the piston 132 from the previous operation of the unit no longer under pressure must be discharged. However, the discharge of this unpressurized fluid is controlled by a pressure valve (not shown). As a result, fluid on the opposite side of the piston 132 is prevented from rapidly discharging through an annular groove 186 and passageways 188 and 190 in the ram 130. In this manner, pressure is built up on the discharge side of the hydraulic system and the fluid in the opening 140 of housing 138, which entered therein by way of the passageways 190, 188, groove 186 and a passageway 192 on a preceding return movement of the housing 138 toward the right, holds the piston 142 against the inner face of the head 146.

A plurality of rods 194 extend between the piston 142 and the pressure plate 164. As the housing 138 moves toward the left, the pressure plate 164 is brought into contact with the work 182 and exerts a clamping force thereagainst due to the concerted action of the rods 194 and piston 142. When the pressure plate 164 engages the work 182, the movement of that plate is stopped and thereafter continued movement of the unit toward the work 182 brings the punch from its retracted position and causes the same to pass through the work. This movement of the punch causes the slidable nut 166 to move 40 45 into the opening 168 and forces the piston 142 away from the cylinder head 146 against the pressure of the fluid on the discharge side of the system.

As the punch 160 passes through the work 182, a slug 196 is punched out and carried by the forward end of the punch into the opening 176 of the die 174 from which it eventually passes to an opening 198 in the supporting member 180 and is dropped exteriorly of the apparatus as additional slugs collect and are advanced therein.

After the punching operation is completed, a reversing valve (not shown) causes fluid under pressure to enter passageways 190 and 188 and thence by way of the annular groove 186 to enter the reduced passageway 200 and the passageway 192. The passageway 192 leads to the opening 140 in the housing 138 and is considerably larger than the passageway 200 which leads to the outer face of the piston 132. The full flow of fluid into opening 140 builds up pressure against the face of the piston 132 before the housing moves away from the work 182. Thereafter, pressure builds up on the piston 132, to 60 65 70 move the housing 138 away from the work 182, withdrawing the punch therefrom as the work is maintained in clamped position. The pressure applied to piston 142 causes it to advance in the opening 140 toward the cylinder head 146 and thereby holds the pressure plate 164

against the work 182 throughout the retracting and stripping of said punch. This movement of the piston 142 also causes the nut 166 to advance in the opening 168 until the shoulder 172 on the nut engages the shoulder 178 formed in the opening 178 at the termination of the retracting movement of the punch 160. Thereafter, the continued movement of the housing 138 away from the work 182 carries the pressure plate 164 and punch 160 away from the work until the housing 138 is fully retracted. During the retraction of the housing 138, the fluid on the forward side of piston 132, no longer under pressure, is discharged through the passageway 184 to a reservoir (not shown).

In Figs. 8, 9 and 10, there is shown another modification of the present invention for punching openings on opposed side walls of channels or other similarly shaped structures. In this form of the invention, a base 210 is provided having a guide plate 212 anchored to the upper surface thereof. A carriage 214 is slidably mounted on the guide plate 212 to move on machined ways 216 on the upper surface thereof between shoulders 218 formed on opposed sides of the guide plate 212. A pair of overlying keeper bars or gibs 220 is anchored to the shoulders 218 to retain the carriage 214 on the guide plate 212 for slidable movement in a manner to be later described. At longitudinally opposed ends of the carriage 214, upwardly directed brackets 222 and 224 are secured.

A ram 226 is fixedly anchored to the bracket 224 and has a piston 228 adapted to register within a bore 230 of a movable hydraulic cylinder 232 in such manner that the ram 226 extends through a cap 234, closing one end of the cylinder. Within the hydraulic cylinder 232, a wall 236 separates the bore 230 from another bore 238 in which a piston 240 is positioned. A cap 242 closes the bore 238 and supports one or a plurality of punches 244 which are threaded into holders 246 which are secured to the cap 242 by a plate 248. A pressure plate 252, having an opening 254 in registry with the punch 244, is also mounted on the cap 242 by bolts 256 which are threaded into nuts 258 extending through the plate 248 and slidably retained within openings 260 provided therefor in the cap 242. The nuts 258 are provided with an annular shoulder 262 which is adapted to be brought into abutting relationship with a shoulder 264 formed in the openings 260 when the plate 252 is in its most forward position.

A channel shaped piece of work 266 is secured in punching position by a work holder 268 carried by the base 210 in position to be engaged by the punch 244. A cooperating die member 270 is carried by the work holder 268, having an opening 272 for receiving the punch 244 at the termination of a punching operation.

The bracket 222 on the left-hand end of the carriage 214, as viewed in the figures, is positioned thereon by a key 274 and bolts 275. The bracket is provided with a cylinder bore 276 containing a piston 278 and enclosed by a cap 280 which is bolted thereto. One or a plurality of punches 282 are mounted on the cap 280 when threaded in the holders 284 which are secured to the cap 280 by a plate 286. A pressure plate 288, having an opening 290 in registry with the punches 282, is slidably mounted on the cap 280 by bolts 292 which are threaded into annular nuts 294 extending through the plate 286. The nuts 294 are slidably disposed within counterbored openings 288

in the cap 280 and are provided with annular heads 296 which are brought into abutting relationship with a shoulder 300 formed in the openings 296 when the pressure plate is in its forward position.

During operation, the punch 282 is adapted to register with a die 302 retained in the adjacent face of the work holder 268 and enters the opening 304 provided therefor in the die 302 at the termination of the punching operation.

Because the ram 226 is fixedly held by the bracket 224 of the carriage 214, the hydraulic cylinder 232 is mounted to be slidably shifted on machined ways 310 provided on the upper surface of the carriage 214 between the shoulders 312 at opposite sides of the carriage. The cylinder 232 is maintained in its position on the ways 310 by overlying keeper bars or gibs 314 which are bolted to the shoulders 312.

In operation, fluid under pressure is delivered from any convenient source by way of line 318 simultaneously to ports 320 and 322. The port 320 delivers the fluid by way of a passageway 324 through the ram 226 into the bore 238 of the hydraulic cylinder 232 to effect movement of that cylinder toward the left, as viewed in Figs. 8 and 9. At the same time, entry of pressurized fluid into the bore 230 acts upon a plunger 326 which is slidably mounted in a collar 328 positioned in the separating wall 236 of the cylinder 232, causing the plunger 326 to move into engagement with the piston 240.

A rod or rods 330 extend between the piston 240 and the pressure plate 252 so that when the piston 232 moves toward the workpiece 266, the pressure plate 252 is maintained in its outermost position while the punch 246 remains in fully retracted position. At or about the same instant the plunger 326 is moved into contact with the piston 240, introduction of pressurized fluid into the port 322 causes a plunger 332 to move to contact the piston 278. The plunger 332 is slidably retained by a collar 334 in the outer wall of the bracket 222 and the plunger 332 moves slidably therein to contact the piston 278. Similar to the previously described rod 330, a rod or rods 336 extend between the piston 278 and the pressure plate 288 to effect clamping of the work 266 on the side opposite pressure plate 252.

Continued movement of the hydraulic cylinder 232 toward the workpiece 266 results in bringing the pressure plate 252 into contact with one side member of the work 266, stopping the movement of the pressure plate 252 and causes the same to exert an initial holding pressure on that side of the work 266.

When the movement of the pressure plate 252 is thus stopped, movement of the cylinder 232 toward the work 266 is stopped and the piston 226 moves the ram 226 outwardly of the bore 230. Movement of the ram 226 in this manner brings about shifting of the carriage 214 toward the right, as viewed in the figures, against the action of springs 338 and 340. As the carriage 214 thus moves, the pressure plate 288 is brought into initial holding engagement with the left-hand side of the work 266 due to the action of rod 336 on piston 278.

With the springs 338 and 340 compressed in this manner, continued input of pressurized fluid into bore 230 retracts the rods 330 and 336 and the pistons 240 and 278 into their respective bores as the punches 244 and 282 move from retracted positions into contact with opposite sides of work 266 and forces the punches through their respec-

tive sides of the work 266. The punches 244 and 282 shear slugs from the work 266 which eventually discharge by way of openings 272 and 384 into opening 342 in the work support 268.

After the openings are punched in this manner in each side of the work 266, the direction of flow of the pressurized fluid is reversed by a reversing valve (not shown) and pressurized fluid is directed by way of a line 344 into ports 346, 348 and 350. As the fluid enters the ports 348 and 350, it acts upon the pistons 240 and 278, respectively, to cause such pistons to exert a force on the rods 330 and 336 for holding the pressure plates 252 and 288 against opposite sides of the workpiece 266 as the punches 244 and 282 are retracted. The fluid entering port 346 and thence passageway 352 to the bore 230 acts upon the piston 232 to effect the return of the cylinder 232 away from the work 266, permitting the springs 340 and 342 to move the bracket 224 away from the work 266. This return movement of the cylinder 232 and the brackets 224 moves the pressure plates 252 and 288 away from the work 266 so that the same may be removed and a new piece substituted therefor.

While the cylinder 232 and the bracket 224 are returned in this fashion, fluid in the unpressurized portions of the device is returned by way of the previously mentioned passageways and ports 324, 322 and 320 into line 318 for return to a reservoir (not shown).

In Figs. 11 and 12, still another form of the invention is illustrated. A base 364 has a guide plate 366 mounted on its upper surface on which a carriage 368 is mounted to move slidably upon machined ways 370 disposed between shoulders 372 formed thereon. Overlying keeper bars 374, which are bolted to the shoulders 372 of the guide plate 366, maintain the carriage 368 on the guide plate 366.

Similarly, a hydraulic cylinder 376 is slidably mounted upon machined ways 378 formed on the upper surface of the carriage 368. The hydraulic cylinder 376 is positioned between shoulders 380 formed on opposed sides of the upper portion of the carriage 368 and overlying keeper bars or gibs 382 are bolted to the shoulders 380 to secure the cylinder 376 thereon.

Brackets 384 and 386 are mounted at opposed longitudinal ends of the carriage 368. A ram 388 is rigidly fixed to the bracket 386 and is provided at its inner end with a piston 390 which is positioned within a bore 392 in the hydraulic cylinder 376 in such manner that the ram 388 extends through a cap 394 which closes the bore 392. In the inner or forward end of the cylinder 376, there is formed another bore 396 in which a piston 398 is positioned to be shifted therein in a manner to be later described. The bore 396 is closed by a cap 400 which has a punch 402 secured thereto by a plate 404. A pressure plate 406 is also mounted on the cap 400 in such manner that the pressure plate may move relative to the punch 402 to effect retraction of that punch and the means for thus mounting the pressure plate 406 (not shown) may be identical to those described in the previous forms of the invention.

A work holder 408 is secured to the base 364 upon which a piece of channel-shaped work 410 may be mounted in such manner that one wall thereof is in adjacent relationship to the pressure plate 406. In the side of the holder 408 adjacent to the pressure plate 406, there is provided a die 412 having an opening centrally thereof which is

axially aligned with the longitudinal axis of the punch 402 into which the punch may extend.

On the bracket 384, a die supporting plate 414 is mounted in adjacent relationship to the opposite side of the work 410. A die 416 is positioned in the plate 414 having an opening 418 centrally thereof in aligned relation with the opening in the previously mentioned die 412. As the punch 402 moves through the work 410, the end of the punch passes through each wall of the workpiece 410 and removes slugs of metal therefrom which are discharged into an opening 420 which is provided in the bracket 384.

In operation, fluid under pressure from any convenient source is introduced by way of a line 422 into a port 424 and thence by way of a passageway 426, formed in the ram 388, into the bore 392 of the hydraulic cylinder 376. When this occurs, the hydraulic cylinder 376 moves in a direction toward the work 410, carrying with it the pressure plate 406. The introduction of pressurized hydraulic fluid into the bore 392 causes a plunger 428, which is slidably mounted in a collar 430 carried by a separating wall 432 between the bores 392 and 396, to move so that the head of the plunger 428 contacts the piston 398.

A rod 434 extends between the piston 398 and the pressure plate 406, and as the latter is brought into engagement with a side wall of the workpiece 410, force is exerted on the pressure plate due to the action of piston 398 on the rod 434 to initially hold the work 410 in punching position. When the pressure plate 406 contacts the side of the workpiece 410, the movement of the pressure plate toward the workpiece 410 is stopped, as is the movement of the hydraulic cylinder 376.

Continued input of fluid under pressure into cylinder 376 causes the piston 390 to move the ram 388 in a direction away from the work 410, effecting movement of the carriage 368 against the action of springs 436 and 438, to move the bracket 384 and the die supporting plate 414 toward the work 410 until the plate contacts the opposite side of the work 410. As soon as the work 410 is clamped between the plates 406 and 414, movement of the carriage 368 is stopped, and thereafter the fluid pressure effects further movement of the hydraulic cylinder 376 toward the work 410. The rod or rods 434, along with the piston 398, retract into the bore 396 as the punch 402 advances from its retracted position and passes first through the wall of the work 410 adjacent thereto and through the holder 408 and thus through the opposite wall of the work 410 to punch openings in each side wall of the work.

After the openings have been punched in each side wall of the work 410, the direction of flow of the unpressurized fluid is reversed by a reversing valve (not shown) and fluid under pressure is simultaneously introduced by way of a line 440 into ports 442 and 444. The fluid passing through port 444 is introduced into the bore 396 to act against the outer face of the piston 398, for holding the pressure plate 406 against the work 410 during the movement of the punch 402 into retracted position. The plate 414 is held against the work 410 during the retracting movement of the cylinder and the punch 402. The fluid introduced into port 442 travels by way of a passageway 446 into the bore 392 to exert a pressure between the piston 390 and cap 394. The cylinder 376 moves away from the work 410 until the punch 402 is brought into its retracted position. Further movement of the cylinder 376 to the right releases the plates 406 and 414 from con-

tact with the work through the action of the springs 436 and 438. The work 410 may then be removed from the holder 408 and a new piece substituted therefor.

Referring to Figs. 13 and 14, the form of the invention therein illustrated embodies a carriage 450 on which a housing 452 is secured by suitable means, herein illustrated as by a key 454 and bolts 455. The carriage 450 is mounted upon suitable ways to permit the carriage and housing 452 to reciprocate thereon. The housing contains a cylindrical opening 456 in which a piston 458 extends from a piston rod 460, the free end of which rod is attached to a mounting adapter 462 which may be secured to a press, standard or other anchoring means. The housing forwardly of the cylinder 456 is provided with a wall 464 containing a collar 466 in which a reciprocal plunger 468 is sealed. The housing also contains a pair of cylindrical openings 470 in which plungers 472 are sealed for reciprocating movement. A collar 474 about the piston rod 460 is sealed to the end of the housing and provided on its outer surface with an annular channel 476 communicating with passageways 478 in communication with the cylindrical openings 470. The piston rod 460 has an annular channel 480 on its exterior surface which communicates through a passageway 482 with a longitudinally extending passageway 484. A passageway 486 extends through the wall of the collar 474 from the annular passageway 476 provided therein. The passageway 486 communicates with a passageway 488 of reduced area which supplies fluid to a shoulder 490 on the piston 458 when the punches are to be retracted. A movable plate 492 is provided in a recess 494 in the forward end of the housing 452 in contact with the plungers 468 and 472. Punches 496 are carried by the housing forwardly of the plate 492, which plate supports a pressure plate 498 which moves with the plate 492 through the rods 500 in contact therewith. The detail of this structure is not illustrated as it follows the same construction as that of the devices hereinbefore illustrated and described.

Fluid is admitted into a passageway 502 in the piston rod 460 to provide a pressure within the cylindrical opening 456 which acts upon the plunger 468 to move the plate 492, rods 500 and pressure plate 498 away from the housing 452. Thereafter, the housing 452 advances on the piston 458 to move the punches 496 toward and through the work as the plate 492 and plungers 468 and 472 retract within the housing as fluid in the cylindrical opening 470 is conducted to the tank (not illustrated).

After the punching operation, the fluid is reversed and pressure is applied through the port 484 into the passageway 478 which applies pressure to the plungers 472 to provide an outward force to the plate 492, rods 500 and the pressure plate 498 to hold the work while pressure builds up between the collar 474 and shoulder 490 to produce the retraction of the housing 452 and therefore of the punches 496. After the punches are withdrawn and the pressure plate 498 has reached its outward position, the further movement of the housing 452 moves the pressure plate from engagement with the work which may then be removed.

Referring to Figs. 15 and 16, a still further form of the invention is illustrated, that wherein the carriage 450 of the housing 452 is mounted in ways 506 and the piston rod 460 is anchored in a standard 508 which projects upwardly from a

table 510 having a standard 512 on the opposite end. The table 510 operates in ways 514 on a bed 516 which has a standard 518 on the end thereof adjacent to the standard 508. The table has a screw 520 threaded therein which is movable through an aperture in the standard 518. The head of the screw engages the standard 518 for limiting its movement to the left, as viewed in the figure. A second adjustable screw 522 is carried by the standard for limiting the movement of the carriage 510 to the right.

The carriage is provided with a cylindrical opening 524, having a piston 526 therein which engages the end of a plunger 528 extending through a collar 530 into engagement with the standard 518. With this construction, the table 510 is shiftable on the base 516 so that a die 532, supported by the standard 512, may adjust itself over a flange on the workpiece after the workpiece has been disposed between the die and the punch 496.

Upon the application of fluid pressure into the cylindrical opening 456, the movement of the housing 452 toward the work first causes the pressure plate 498 to engage the work, after which the movement of the housing 452 ceases and the piston 458 moves outward of the cylindrical opening 456 to thereby move the carriage 510 to the right, as viewed in the figure, and advance the die 532 into engagement with the work. Continued application of fluid into the cylindrical opening 456 again advances the housing 452 to the left to thereby move the punches 496 through the work. Upon the reversal of the flow of fluid from the aperture 502 to the aperture 484 in the piston rod, fluid is also directed through the conduit 534 to the cylinder 524 to thereby advance the table 510 to the left after the punch 496 has been withdrawn from the work to clear the die 532 from the flange of the work so that the work may be removed.

Referring to Figs. 18 and 19, a similar device as that illustrated in Figs. 15 and 16 is shown, which is of very narrow construction. In this arrangement, a housing 536 is provided with a cylindrical aperture 456 containing the piston 458 having the piston rod 460 provided with the passageways 502 and 484. The piston rod is secured to the carriage 508 which is shiftable on the base 538. The housing 536 is shiftable in ways 540 on the carriage 508. The die 532 is supported on the standard 512 on the table 510 and the pressure plate 498 is supported on the guide elements 542 secured to the die supporting plate 544 attached to the forward end of the housing 536. A cylindrical opening 546 is provided forwardly of the cylindrical opening 456 in the housing 536, the wall 548 therebetween having a sleeve bushing 550 extending therethrough in which a plunger 552 reciprocates. The plunger abuts a piston 554 which is sealed to the wall of the cylindrical opening 546 and which engages a rod or rods 556 which abut the pressure plate 498. A passageway 558 leads from the rear end of the cylindrical opening 546 to an annular aperture 560 provided about the collar 474. With this arrangement, the application of fluid to the side of the piston 554 adjacent to the wall 548 occurs in the same manner as that of the structure of Figs. 13 and 14, hereinabove specifically described, upon the reversal of flow of fluid. This produces the withdrawal of the punches from the work, the subsequent withdrawal of the pressure plate and the shifting of the supporting table to have the die and pressure plate free of the work. By

having the cylindrical aperture 546 aligned with the aperture 456, the very narrow construction of the device is thereby obtained. It is to be understood that instead of providing the cylindrical opening 546 forwardly of the cylindrical opening 456 in the housing 536, the housing 452 illustrated in Figs. 13 and 14 may be substituted therefor by mounting the housing in a vertical instead of a horizontal plane to thereby maintain the narrow construction and provide a support for a plurality of punches in a substantially vertical plane within the width of the device.

In the constructions herein illustrated, the application of fluid to the secondary cylinders for advancing the pistons therein and forcing the pressure plates against the work, produces a reactive force which moves the housings or main piston sufficiently to withdraw the punch from the work. After the movement of the secondary pistons has terminated, the further application of fluid into the main cylinder continues the retractive movement of the housing until the main piston has completed its stroke relative to the cylinder, and the housing or piston has returned to its initial position.

Referring more specifically to Figs. 13 and 14, the fluid for retracting the housing enters the passageway 484, the annular passageway 482, the passageway 478, to the cylindrical openings 470 to force the plate 492 forwardly to thereby produce the retraction of the housing over the plate and the withdrawal of the punches 496 from the work.

It will be noted in Figs. 13 and 14 that the plate 492 and pistons 472 are in the most forward position, while the housing 452 is also in the most forward position. This condition would occur when the advancement of the elements takes place without the pressure plate 498 contacting the work. The fluid from the passageway 484 would pass through the passageway 482 to produce the retractive movement of the housing 452 until the annular passageway 482 advances beyond the end of the sleeve 474, at which time the introduction of the larger volume of fluid into the area of the shoulder 498 would produce the rapid return of the housing. The aperture 488 is small compared to the aperture 486, in the order of approximately one to ten, to assure a greater delivery of fluid to the cylindrical openings 470. When a greater length is provided to the cylinder 456 to provide a longer stroke to the housing 452, the passageway 484 may be extended, as at 562, and connected by a passageway 564 in communication with the shoulder 498 so as to be available to admit or bleed off fluid from the shoulder area when the annular passageway 482 has cut off the return supply of fluid from the passageway 488 to the passageway 484.

It will be noted that in the above mentioned patent, a relief valve is employed for relieving the pressure of fluid on the pressure plate as the housing advances to produce the operation on the work. This pressure valve is eliminated in the present construction through the differential areas provided between the plungers 92, 326, 333, 428, 468 and 552 and the cylinder in which the end projects. With this arrangement, the initial pressure in the cylinders forces the plunger forwardly to advance the pressure plate to its advanced position as the housing advances the pressure plate into contact with the work. The further application of pressurized fluid to the cylinder continues the movement of the housing while permitting the plunger to retract within

the cylindrical opening during the punching operation. The use of the relief valve or the plunger projecting within the main cylinder provides a predetermined hold-down pressure for the work before and during the punching operation.

The structure of the present invention readily lends itself to the construction of a variety of types of punching machines. Any number of the devices may be assembled on a bed in predetermined relation to the work which is clamped in position therein. The devices are operated serially or simultaneously to apply pressure to the pressure plate which is moved with the punches into engagement with the work. This is usually accomplished by fluid supplied in large volume and at low pressure in the order of 500 to 1000 p. s. i. Thereafter, fluid is supplied in low volume and at high pressure in the order of 5000 to 10,000 p. s. i. to force the punch or punches through the work. The withdrawal of the punches and the retraction of the devices to their initial positions are accomplished by the fluid supplied at low pressure.

It is to be understood that in any of the constructions herein illustrated the cylinder may move on a fixed piston or be maintained stationary while the piston is free to move. It is further to be understood that fluid can be directed into the cylinders of the punch retracting pistons through passageways in the main cylinder wall from the piston rod, as shown in Figs. 3 and 13, thereby eliminating the necessity of employing flexible conduits for conducting fluid thereto as illustrated.

35 What is claimed is:

1. In a device for operating on a piece of work, a cylinder and piston one of which is anchored in fixed position, a second cylinder and piston, a pressure plate associated with said second cylinder and piston, a plunger in fluid communication with said first cylinder and in engagement with said second piston for clamping the work during the punching operation, and a punch carried by said first cylinder and piston and advanced through the work thereby after the pressure plate engages and holds the work, said punch being retractable from the work by the operation of the second cylinder and piston while forcing the pressure plate toward the work when pressure is relieved from said first cylinder and piston.

2. In a device for operating on a piece of work, a cylinder and piston one of which is anchored in fixed position, a pressure plate associated with said cylinder and piston, a plunger, a second cylinder and piston engaging the pressure plate and movable by said plunger, and means for supporting a punch by said first cylinder and piston, said plunger being of smaller diameter than the first piston so that when fluid is delivered simultaneously to the plunger and piston the pressure plate and second piston will move to advanced position and be moved by the cylinder and piston to engage and hold the work as the punch is advanced therethrough as the plunger retracts against the pressure applied thereto.

3. In a device for punching holes in a workpiece, a first cylinder and piston having a punch associated therewith for performing a punching operation, a plunger extending from said cylinder for initially applying pressure on the workpiece and retractable against the pressure therein during the punching operation, and a second cylinder and piston of substantially greater diameter than said plunger for retracting the

punch from the work as the work is held thereby.

4. In a device for punching holes in a work-piece, a first cylinder and piston having a punch associated therewith for performing a punching operation, a plunger extending from said cylinder and operated by the fluid when applied to the cylinder for initially applying pressure on the workpiece and retractable in the cylinder against the pressure therein during the punching operation, and a second cylinder and piston for retracting the punch from the work as the work is held thereby, the second cylinder, piston and punch being retractable from the work by the operation of the first cylinder and piston thereafter.

5. In a device for holding a workpiece for performing a punching operation thereon including, in combination, a cylinder and piston one of which is secured in fixed position, a pressure plate, and a plunger engaging said pressure plate and projecting into said cylinder to be independently actuated by the fluid therein, said plunger being of smaller diameter than the diameter of the cylinder for actuating said pressure plate away from said cylinder independently of the piston when fluid under pressure is directed thereinto to relatively advance said cylinder and piston in the direction said pressure plate has advanced.

6. In a device for holding a workpiece while performing an operation thereon including, in combination, a movable cylinder, a piston in said cylinder, a pressure plate supported for limited movement on said cylinder, a plunger engaging said pressure plate and projecting into said cylinder, said plunger being of a diameter substantially less than the diameter of the cylinder, and a second cylinder and piston associated with said first cylinder disposed in position to apply pressure to said pressure plate when pressure is reversed in said first cylinder, the reaction to which moves the first cylinder away from the pressure plate.

7. In a device for holding the work and performing a punching operation thereon including, in combination, a fixed cylinder, a movable piston in said cylinder, a slide moved by said piston, a pressure plate mounted on said slide for limited movement, means for supporting a punch on said slide, and a second cylinder and piston carried by said slide having operative engagement with said pressure plate and movable by the first said piston into engagement with the work which thereafter remains stationary while the punching operation occurs.

8. In a device for holding the work and performing a punching operation thereon including, in combination, a fixed cylinder, a movable piston in said cylinder, a slide movable by said piston, a pressure plate mounted on said slide for limited movement, means for supporting a punch on said slide, and a second cylinder and piston carried by said slide having operative engagement with said pressure plate and movable by the first said piston into engagement with the work which thereafter remains stationary while the punching operation occurs, said second cylinder and piston applying a holding force to the pressure plate and work after the pressure is reversed in said first cylinder and applied to said second cylinder, the reaction to which retracts the slide an amount to withdraw the punch from the work.

9. In a device for holding the work and performing a punching operation thereon including, in combination, a cylinder, a movable piston in

said cylinder, a slide movable by said piston, a pressure plate mounted on said slide for limited movement, means for supporting a punch on said slide, a plunger on said slide for advancing the pressure plate therefrom when fluid directed into the cylinder is conducted thereto, and a second cylinder and piston carried by said slide having operative engagement with said pressure plate, said pressure plate being adapted to be moved by the first said cylinder into engagement with the work which thereafter remains stationary while the punching operation occurs and the plunger retracts, said second cylinder and piston applying a holding force to the pressure plate and work after the pressure is reversed on said first cylinder, the reaction to which retracts the first cylinder an amount to withdraw the punch from the work, said first cylinder thereafter returning the slide to its initial position.

10. In a device for securing the work while punching an aperture therethrough, a cylinder and piston and means by which one portion thereof is secured in fixed position, a slide operated by the movable portion of said cylinder and piston, a second cylinder and piston in said slide, a plunger carried by the slide, a pressure plate supported by the slide and engaged by said plunger, a conduit conducting fluid to said first cylinder and said plunger, and a punch carried by the slide and projectable beyond the pressure plate whereby the relative movement between the first said cylinder and piston advances the slide to move the pressure plate into engagement with the work through which the punch is thereafter forced, the punches being retracted from the work thereafter by the operation of the second cylinder and piston when applying a holding force to the plate after the pressure is relieved from said first cylinder.

11. In combination with a device for holding the work and performing a punching operation thereon, a fixed cylinder, a piston movable therein, a slide movable by said piston, means for supporting a punch on said slide, a pair of spaced cylinders and pistons provided in said movable slide, a plunger on said slide of a diameter less than the diameter of the cylinder, a conduit conducting fluid to said cylinder and said plunger, and a pressure plate carried by said slide for limited movement thereon engageable by said plunger and said spaced pistons for applying a forward movement thereto whereby the movement of the slide by said first piston applies a pressure to the plunger and advances the pressure plate into engagement with the work through which the punches are thereafter forced, and after pressure is relieved from the first cylinder and piston, the pressure on the spaced pistons applying a forward pressure on the pressure plate and a retractive force on the slide for withdrawing the punches from the work.

12. In a device for holding and punching apertures in workpieces, a reciprocable housing having a central cylinder containing a fixed piston, an annular cylinder and piston disposed around said first cylinder and piston, a pressure plate carried by said housing for limited movement under the control of said annular piston, and means on said housing for supporting the punch whereby the advancement of the housing on the fixed piston moves the pressure plate into engagement with the work and the punch through the work thereafter for performing the punching operation.

13. In a device for holding and punching aper-

tures in workpieces, a reciprocable housing having a central cylinder containing a fixed piston, an annular cylinder and piston disposed around said first cylinder and piston, a pressure plate carried by said housing for limited movement under the control of said annular piston, and means on said housing for supporting the punch whereby the advancement of the housing on the fixed piston moves the pressure plate into engagement with the work and the punch through the work thereafter for performing the punching operation, the application of pressure to the annular piston and a reversal of pressure on the first cylinder and piston producing the retraction of the punch and the application of pressure to the pressure plate.

14. In combination with a device for holding the work and performing a punching operation thereon including, in combination, a table, a cylinder and piston one element of which is secured to one end of the table, a pair of cylinders and pistons one fixed to the opposite end of the table from the first said cylinder and piston, the other of which is shiftable relative to the table by the first said cylinder and piston, a pressure plate carried by each of said pairs of cylinders and pistons for limited movement and operated toward each other with a predetermined force which is less than that applied by said first cylinder and piston to move the pressure plates into engagement with opposite sides of the work as the table is shifted on the base thereby, and a punch carried by each of said pairs of cylinders and pistons, the continued operation of the first cylinder and piston producing further relative movement of the table and the advancement of the punches through the work, the reversal of fluid thereafter in the first cylinder and piston and the application of greater pressure to the pressure plate by the second cylinder and piston securely holding the work while the punches are retracted therefrom.

15. In combination with a device for holding the work and performing a punching operation thereon including, in combination, a table, a cylinder and piston one element of which is secured to one end of the table, a pair of cylinders and pistons one fixed to the opposite end of the table from the first said cylinder and piston, the other of which is shiftable relative to the table by the first said cylinder and piston, a pressure plate carried by each of said pairs of cylinders and pistons for limited movement and operated toward each other with a predetermined force which is less than that applied by said first cylinder and piston to move the pressure plates into engagement with opposite sides of the work as the table is shifted on the base thereby, a punch carried by each of said pairs of cylinders and pistons, the continued operation of the first cylinder and piston producing further relative movement of the table and the advancement of the punches through the work, the reversal of fluid thereafter in the first cylinder and piston and the application of greater pressure to the pressure plate by the second cylinder and piston securely holding the work while the punches are retracted therefrom, and means for positioning said table on the base.

16. In a device for punching holes in the spaced walls of a channel element which includes, in combination, a shiftable carriage, a fixed support for the work, a cylinder and piston one of which is secured to one end of the carriage, a pair of cylinders and pistons one of which is mounted on

the opposite end of the carriage from that of the first cylinder and piston, the other of which is mounted for movement by said first cylinder and piston relative to said carriage, pressure plates supported by said pair of cylinders for limited movement outwardly thereof toward each other, and means on said pair of cylinders for supporting a punch whereby the application of pressure to the first cylinder and piston advances the pressure plates into engagement with the spaced walls of the channel element through the shifting of the carriage which is further shifted thereafter as the punches are advanced beyond the pressure plate through the spaced walls of the element.

17. In a device for punching holes in the spaced walls of a channel element which includes, in combination, a shiftable carriage, a fixed support for the work, a cylinder and piston one of which is secured to one end of the carriage, a pair of cylinders and pistons one of which is mounted on the opposite end of the carriage from that of the first cylinder and piston, the other of which is mounted for movement by said first cylinder and piston relative to said carriage, pressure plates supported by said pair of cylinders for limited movement outwardly thereof toward each other, and means on said pair of cylinders for supporting a punch whereby the application of pressure to the first cylinder and piston advances the pressure plates into engagement with the spaced walls of the channel element through the shifting of the carriage which is further shifted thereafter as the punches are advanced beyond the pressure plates through the spaced walls of the element, the application of pressure to the pair of pistons upon the reversal of the fluid in the first said cylinder and piston procuring the clamping of the pressure plates against the work and the retraction of the punches from the walls of the element.

18. In a device for punching holes in the spaced walls of a channel element which includes, in combination, a shiftable carriage, a fixed support for the work, a cylinder and piston one of which is secured to one end of the carriage, a pair of cylinders and pistons one of which is mounted on the opposite end of the carriage from that of the first cylinder and piston, the other of which is mounted for movement by said first cylinder and piston relative to said carriage, pressure plates supported by said pair of cylinders for limited movement outwardly thereof toward each other, and means on said pair of cylinders for supporting a punch whereby the application of pressure to the first cylinder and piston advances the pressure plates into engagement with the spaced walls of the channel element through the shifting of the carriage which is further shifted thereafter as the punches are advanced beyond the pressure plates through the spaced walls of the element, the application of pressure to the pair of pistons upon the reversal of the fluid in the first said cylinder and piston procuring the clamping of the pressure plates against the work and the retraction of the punches from the walls of the element, the punches and pressure plate being further removed away from each other to their initial relative positions by the actuation of the first cylinder and piston.

19. In a device for punching holes in the spaced walls of a channel element which includes, in combination, a shiftable carriage, a fixed support for the work, a cylinder and piston one of which is secured to one end of the carriage, a pair of cylinders and pistons one of which is mounted on the opposite end of the carriage from that of

the first cylinder and piston, the other of which is mounted for movement by said first cylinder and piston relative to said carriage, pressure plates supported by said pair of cylinders for limited movement outwardly thereof toward each other, means on said pair of cylinders for supporting a punch whereby the application of pressure to the first cylinder and piston advances the pressure plates into engagement with the spaced walls of the channel element through the shifting of the carriage which is further shifted thereafter as the punches are advanced beyond the pressure plates through the spaced walls of the element, the application of pressure to the pair of pistons upon the reversal of the fluid in the first said cylinder and piston procuring the clamping of the pressure plates against the work and the retraction of the punches from the walls of the element, the punches and pressure plate being further removed away from each other to their initial relative positions by the actuation of the first cylinder and piston, and means for shifting said carriage to its initial position relative to the stationary work holder.

20. In a device for holding and performing a work operation on a workpiece, a main cylinder and piston, a pressure plate, a second cylinder and piston engaging and moving said pressure plate, and a plunger in said main cylinder of less diameter than said main cylinder for applying initial pressure to said pressure plate when pressure is applied to said main cylinder and piston, said second cylinder and piston being of greater diameter than said plunger for applying a forward holding force to said pressure plate sufficient to produce the relative retraction of said first cylinder and piston when the initial pressure is released therefrom.

21. In a device for clamping and holding a workpiece, a housing containing a first cylinder and piston, a pressure plate mounted on said housing for limited movement, a plunger projecting in said cylinder contacting said plate and having a diameter substantially less than the diameter of the cylinder, and a pair of spaced cylinders and pistons in said housing disposed to have the pistons contact said pressure plate whereby the plate is held in advanced position by the operation of the plunger when fluid is initially applied to said first cylinder and piston to advance the pressure plate and housing to have the work engaged by the pressure plate which retracts toward the housing as the housing continues to advance toward the workpiece.

22. In a device for clamping and holding a work piece, a housing containing a first cylinder and piston, a pressure plate mounted on said housing for limited movement, a plunger projecting in said cylinder contacting said plate and having a diameter substantially less than the diameter of the cylinder, and a pair of spaced cylinders and pistons in said housing disposed to have the pistons contact said pressure plate whereby the plate is held in advanced position by the operation of the plunger when fluid is initially applied to said first cylinder and piston to advance the pressure plate and housing to have the work engaged by the pressure plate which retracts toward the housing as the housing continues to advance toward the workpiece, the reversal of pressure on the first cylinder and piston and the application of pressure to the pair of cylinders and pistons causing the pair of pistons to apply a holding pressure to the pressure plate, the reactive force of which moves

the housing away from the work, after which the first cylinder and piston return the housing to its initial position when fluid is reversed therein.

5 23. In a device for clamping and holding a workpiece, a housing containing a first cylinder and piston, a pressure plate mounted on said housing for limited movement, a plunger projecting in said cylinder contacting said plate and having a diameter substantially less than the diameter of the cylinder, a pair of spaced cylinders and pistons in said housing disposed to have the pistons contact said pressure plate whereby the plate is held in advanced position by the operation of the plunger when fluid is initially applied to said first cylinder and piston to advance the pressure plate and housing to have the work engaged by the pressure plate which retracts toward the housing as the housing continues to advance toward the workpiece, the reversal of pressure on the first cylinder and piston and the application of pressure to the pair of cylinders and pistons causing the pair of pistons to apply a holding pressure to the pressure plate, the reactive force of which moves the housing away from the work, after which the first cylinder and piston return the housing to its initial position when fluid is reversed therein, a bed, a carriage on said bed to which one end of said main piston is secured, means on the opposite end of the carriage for supporting a work engaging element which is advanced into engagement with the work after the pressure plate is advanced thereagainst by the movement of the first cylinder and piston through the shifting of the carriage, and a cylinder and piston on said carriage by which said carriage is moved to its initial position.

25 24. In a device for holding the work and performing a punching operation thereon including, in combination, a fixed cylinder, a movable piston within said cylinder, a slide secured to said piston, a second piston and cylinder on said slide a pressure plate carried by said slide in advance of said second piston, rod means connecting said second piston to said pressure plate, a plunger in said second cylinder on the opposite side thereof from said pressure plate for advancing the piston of said second cylinder and the pressure plate, a conduit connected to said plunger and to said first cylinder from the end thereof opposite to the slide, and a punch carried by said slide operable relative to said pressure plate.

40 25. In a device for holding the work and performing a punching operation thereon including, in combination, a fixed piston, a cylinder movable over said piston, a second piston and cylinder carried by said first cylinder, a plunger operated by fluid pressure in said first cylinder and operatively engaging said second piston for advancing it in the second cylinder, a pressure plate carried by said first cylinder forwardly of said second cylinder, rod means interconnecting the second piston and pressure plate, and a punch carried by said first cylinder forwardly of said second cylinder and movable relative to said pressure plate.

45 26. In a device for holding the work and performing a punching operation thereon including, in combination, a fixed piston, a cylinder movable over said piston, a second piston and cylinder carried by said first cylinder, a plunger operated by fluid pressure in said first cylinder and operatively engaging said second piston for advancing it in the second cylinder, a pressure plate carried by said first cylinder forwardly of

said second cylinder, rod means interconnecting the second piston and pressure plate, a punch carried by said first cylinder forwardly of said second cylinder and movable relative to said pressure plate, a slide to which said first piston is fixed, a third cylinder and piston carried by the opposite end of the slide from that to which the first piston is secured, a second plunger projecting into the third cylinder in contact with the piston thereof, means by which a fluid pressure is applied to the second plunger when fluid pressure is applied to the first cylinder and plunger, a pressure plate carried by said third cylinder, rod means interconnecting the pressure plate to said third piston, and a punch carried by said third cylinder movable relative to said pressure plate.

27. In a device for holding the work and performing a punching operation thereon including, in combination, a fixed piston, a cylinder movable over said piston, a second piston and cylinder carried by said first cylinder, a plunger operated by fluid pressure in said first cylinder and operatively engaging said second piston for advancing it in the second cylinder, a pressure plate carried by said first cylinder forwardly of said second cylinder, rod means interconnecting the second piston and pressure plate, a punch car-

ried by said first cylinder forwardly of said second cylinder and movable relative to said pressure plate, a slide to which said first piston is fixed, a third cylinder and piston carried by the opposite end of the slide from that to which the first piston is secured, a second plunger projecting into the third cylinder in contact with the piston thereof, means by which a fluid pressure is applied to the second plunger when fluid pressure is applied to the first cylinder and plunger, a pressure plate carried by said third cylinder, rod means interconnecting the pressure plate to said third piston, a punch carried by said third cylinder movable relative to said pressure plate, a fixed work support between said pressure plates, and means for centering said slide relative to said work support.
